UNITED STATES PATENT OFFICE.

WILLIAM HENRY THORNE, OF EXMOUTH, ASSIGNOR TO SPENCER, TURNER & BOLDERO, OF LONDON, ENGLAND.

DESIGN FOR A TEA-CANISTER.

SPECIFICATION forming part of Design No. 20,951, dated July 21, 1891.

Application filed March 11, 1891. Serial No. 384,657. Term of patent 3½ years. Patented in England January 3, 1889, No. 116,823, and in Victoria January 2, 1891, No. 5774.

To all whom it may concern:

Be it known that I, WILLIAM HENRY THORNE, a subject of the Queen of Great Britain and Ireland, residing at Exmouth, in the county of Devon, England, have invented and produced a new and original Design for a Canister for Holding Tea, Coffee, or the Like, (patented in Great Britain January 3, 1889, No. 116,823, and in Victoria January 2, 1891, No. 5774,) of which the following is a specification, reference being had to the accompanying drawings, forming part thereof.

Figure 1 a side elevation, Fig. 2 a plan, and Fig. 3 a cross-section on the line *a a'* of Fig. 1, these three views being deemed necessary to fully illustrate my design.

The leading feature of this design for a canister is the shape and configuration thereof, which approximates that of a surf-boat or life-boat with similar tapering and rising ends and with a centrally-disposed and elevated cover having a horizontal upper surface. The opening flange *C* at the top is rectangular, with a cover *D*, having a horizontally-dis-

posed upper surface. The upper surfaces *B* 25 of the canister-body at each end of the cover *D* are slightly concave and tapering and rising toward the respective elevated pointed ends. The sides *A A* are externally convex both vertically and horizontally and extend 30 downwardly to the center line in a shape similar to an inverted Gothic arch, and such sides are extended upwardly to the ends at the edges of the tapering portions of the top.

I claim—

The design of the shape and configuration of the canister, substantially as represented.

In witness whereof I have hereunto signed my name in the presence of two subscribing witnesses.

WILLIAM HENRY THORNE.

Witnesses:

WILSON STUCKEY,
Notary Public, Brighton, Sussex, England.

LEWIS B. WELLS,
Clerk to Messrs. Stuckey, Son & Pope, Solrs.,
Brighton.
